CLAIM

The ornamental design for a can golf tee, as shown and described.

DESCRIPTION

FIG. 1 is a perspective view of a can golf tee with environment;

FIG. 2 is a front elevation view thereof without environment;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view of the can golf tee of FIG. 1 without environment.

The broken lines shown in FIG. 1 illustrating a golf ball are directed to environment and form no part of the claimed design. Additional broken lines show portions of the can golf tee which form no part of the claimed design.

1 Claim, 8 Drawing Sheets
